UNITED STATES PATENT OFFICE.

JOHN THOMSON, OF NEW YORK, AND FRANCIS A. J. FITZ GERALD, OF NIAGARA FALLS, NEW YORK, ASSIGNORS TO JOHN THOMSON PRESS COMPANY, OF JERSEY CITY, NEW JERSEY, A CORPORATION OF NEW JERSEY.

CONDENSER IN THE METALLURGY OF ZINC.

1,219,193.

Specification of Letters Patent.

Patented Mar. 13, 1917.

Application filed June 21, 1916. Serial No. 104,837.

To all whom it may concern:

Be it known that we, JOHN THOMPSON and FRANCIS A. J. FITZ GERALD, citizens of the United States, and residents, respectively, of 5 the borough of Manhattan, city of New York, county and State of New York, and of Niagara Falls, county of Niagara, State of New York, have invented certain new and useful Improvements in Condensers in 10 the Metallurgy of Zinc, of which the following is a specification, reference being made to the accompanying drawings, forming a part hereof.

This invention relates to the metallurgy 15 of zinc and particularly pertains to condensers which are used in conjunction with or which constitute a part of an electric furnace that is adapted for purifying low-grade spelter by the distillation thereof. 20 Some of the objects of the invention are to obtain a high capacity in an integral condensing unit, to condense zinc-fume to liquid metal and to separately precipitate cadmium-fume, when such is present, in the 25 form of an isolated powder, or as a concentrate with zinc-dust.

In said drawings which present a preferred embodiment of the invention,

Figure 1 is a vertical, longitudinal center section and elevation of a brick housing having the condenser mounted therein, all being at the right-hand side of an indicated electric furnace, A, in which the fume is produced.

Fig. 2 is an end elevation of the aforesaid housing showing a portion of the condensing apparatus.

Fig. 3 is a horizontal center section of the liquid condenser and the precipitator, and 40 is a view taken as on the lines B and C of Figs. 1 and 4, or as viewed from above with respect to Fig. 1.

Fig. 4 is a half center section, taken as on the line D, and a half side elevation looking at the condenser in the direction indicated by arrow E of Fig. 3; and

Fig. 5 is a revolved transverse section of the powder precipitator and is a view taken as on the line F of Fig. 2.

In Figs. 3, 4 and 5 the parts are drawn to 50 a larger scale than in Figs. 1 and 2.

It has been abundantly proven that the thermal control of a plurality of condensers, which receive zinc-fume from a single source of supply, is much more difficult than 55 when the condenser itself is a self-contained unit.

In an electric furnace which can distil zinc at the rate of, say, one hundred and twenty pounds an hour, this means that 60 about twelve cubic feet of fume per minute has to be dealt with. The thermal duty is probably quite as severe to emit as to receive heat-units; hence, in a structure having an adequate volumetric capacity, made 65 of material immune to air-burning and wholly free from checks or cracks, the difficulty of construction is pronounced.

The practice, hitherto, has been to utilize the condenser itself as a container of the 70 condensed liquid metal; which, from time to time, is partially or wholly tapped off.

When zinc is contaminated with cadmium, which is usually in the proportion of less than one per centum, it can be more or less 75 extracted by fractional distillation, which requires a furnace of special construction; by fractional condensation, which produces a minimum by-product of zinc high in cadmium, and by burning at the condenser-vent, 80 which entails its loss as well as a certain amount of entrained zinc-fume.

A brief analysis of the procedure and what is to be accomplished will now be given in that this will serve to clarify the 85 following detail description. If there is no cadmium to be dealt with, all of the zinc-fume is to be condensed in a casing from which the hot liquid metal escapes as and when produced and it is then collected in a 90 separate container from which it is intermittently withdrawn.

Theoretically, zinc and cadmium begin to slowly condense at about, or somewhat below, their respective conventional "boiling" points, 930° and 780° C.; but the rate of liquefaction proceeds progressively and rapidly with fall of temperature and in contact with an adequate coalescing surface. The conventional chilling, or "freezing" points are 419° for zinc and 320° C. for cadmium.

Normally, the amount of the cadmium content in spelter, such as would usually be distilled, ranges from 0.20 to 0.50 per cent.; hence its volume, as fume, would range but from about 25 to 50 cubic feet in a ton of zinc.

If cadmium fume is mingled with the zinc-fume, then the latter is not to be completely condensed, the thermicity being so controlled that the major portion of the condensation is effected between a relatively short range in temperature, say from about 900° C., as a maximum falling to about 750° to 700° as minimums.

Thus, the residual fume remaining in the condenser will be a gaseous concentrate, high in cadmium. For the present purpose, let it be assumed that it is half and half. This low-temperature fume-concentrate is then to be conducted to a chilling prolong where in it is precipitated as powder and more or less automatically separated in subchambers, ranging from zinc-dust, to zinc-cadmium dust, to cadmium-dust.

The means for realizing the foregoing results may be variously modified and arranged, according to existing circumstances; but those which will now be described have proven effective and will serve as an example based upon practical performance.

The dominant elements of the system are as follows: A, denotes a furnace in which the fume is produced and from whence it passes, as through a throat or conduit I to a condenser J mounted in a brick housing K. L is the liquid zinc receiver having a draw-off spout M, and N is the dust or powder precipitator.

The condenser may be readily and inexpensively formed from two shallow pans, 6, 7, each a duplicate of the other, having flanges, 8, 9, which may be availed of for the application of suitable clamps, the latter not being shown. One end of each pan is partially removed so that, when the two are set together, they form a port 10 whose area approximates that of the furnace-throat.

Within the casing are a series of staggered baffle-plates, as 12, conveniently sustained by being strung upon a central rod, 13, whereby the fume is caused to travel in a sinuous course, as shown by arrows a, and

to also impinge upon a coalescing surface of large area; but, in the present case, these features are not introduced as the subject-matter to serve the basis for specific claims.

The condenser, when thus assembled, is cemented to the throat, as at 14, and is set in the brick-housing with a sharp down-slope therefrom, or as shown at a decline of about 10°, being supported as at 15, 16, Fig. 1.

At the end of and beneath the condenser, farthest from the throat, the extraneous zinc receptacle is set, which may be, as shown, an ordinary crucible provided with a tap-hole, 17. The interior of the condenser is connected to the receptacle by a hole, 18, formed in the bottom pan.

By a proper disposal of the baffle-plates and having regard to their number, and by controlling the temperature and the volume of the entering fume, the condensation may be distributed through a major portion or all of the condenser-casing, or a certain residual of fume may be taken off through a vent.

Due to the sharp decline of the condenser, the liquefied metal trickles down the baffle-plates; and runs rapidly along the bottom and thence passes down through the opening 90 in the casing, as and when condensed, to the underlying receptacle, as arrow v, Fig. 1.

The consequences are that the temperature of the condenser casing can readily be maintained, for any given rate of fume-volume, 95 with the utmost uniformity, and should a fissure develop in any portion of the casing, or at the flange-joint, the escaping fume will burn to ZnO and automatically seal the leak. In other words, the casing is solely a fume 100 container.

The brick housing is provided with horizontal flues, as 18, 19; vertical connecting flues, as 20, and side openings, as 21. The zinc receptacle is preferably set on a spaced, 105 brick grid, indicated by 22, and there is an opening, 23, in the front wall through which it may be conveniently inserted or removed, without disturbing the condenser casing, its joint, at the condenser, being cemented, as 110 at 24.

The objects of the flues and side-openings are, firstly, for convenience in preliminarily heating the condenser and receptacle, as by means of charcoal fires in the flue 19 and on the hearth, 25, and to thereafter utilize them for controlling the rate of radiation by flow of cold air therethrough. These can be used simultaneously or separately, as desired. An additional control of the condenser temperature is at the top, as by partially or wholly removing, or by adding bricks upon, the cover-plates, 26. In this wise, the rate of heat-radiation is under such complete

control it can be said that essentially any zone of the condenser-casing may be uniformly held to within a few degrees of a desired temperature. Moreover, such control may be readily attained and when established little or no further attention is necessary. The concluding coördinating features of the invention will now be described in detail.

10 The prolong or anterior chamber member, as depicted in the drawings, is formed of a metal cylinder, 27, open at one end and inclosed by an integral head, 27^a, at the other, on which is a bored spud, 28, adapted to be inserted in a side-opening in one of the pans, preferably at the termination of the sinuous fume-circuit. The main body of the prolong projects horizontally into the atmosphere, as through the opening 29, 15 in the brick housing. Within this cylinder are a series of staggered baffle-plates, 30, mounted upon a central rod, 31, as in the instance of the condenser. These baffles are provided with wings, as 32, which are disposed along the lower surface of the cylinder, as best shown in the revolved or vertical delineation, Fig. 5. The outer, or end plate, 33, is wholly cylindrical and serves as an inclosing head, being made air-tight 20 by cement, as at 34, but easily removable when desired.

Now, bearing in mind that any desired aliquot part of the condenser-fume, which, with respect to its entering temperature at 35 the throat, will be relatively cool, can be retained as a residuum (in practice, say, about one or two per cent.) and will thence flow into the prolong, the consequence is that it is chilled in the air-cooled cylinder 40 and by impingement upon the baffle-plates being precipitated as a powder, *w*, see Fig. 5. Moreover, as the chilling, or "freezing," temperature of cadmium is about 100° C., below that of zinc, there will be an accumulation of dust in the spaces between the wings of the baffle-plates becoming progressively higher in cadmium toward the far end of the cylinder, or as from *n* to *r*, to *s*, to *x*, to *z*. Then by carefully withdrawing the central rod with its attached plates, and collecting the powder from each compartment a separation of the different powders or concentrates thereof can be effected.

55 If there is no cadmium in the spelter, the prolong needs simply be removed, in which instance the usual circulating, or flame-vent, would be in the condenser casing; but if powder is being precipitated the vent would be in the far end of the prolong, as at 35, Fig. 5.

Obviously, the prolong may readily be

water-cooled, if a high rate of precipitation is desired, as by means of an encircling pipe-coil. So, too, as has been previously proposed, a further control of the rate of flow of fume therein can be effected by means of suction, preferably produced by an inducing flow of air under moderate pressure applied at the far end of the prolong. 65 70

To indicate the commercial practicability of this invention it can be stated that a single condenser, having a depth of 6 inches with a breadth and width of about 28 x 48 inches, has condensed over one and a half 75 tons of liquid zinc in 24 hours, and that a powder concentrate has been precipitated containing nearly 29 per cent. of cadmium to 71 per cent. of zinc from spelter which originally contained less than fifteen hundredths of one per cent., equivalent to three pounds in a ton of zinc. 80

What is claimed is:

1. In the metallurgy of zinc, a condenser, set at a decline from the source of fume-supply and in which liquid metal is produced but not retained, combined with a separate underlying zinc receptacle disposed in such manner that it can be removed without disturbing the said condenser. 85 90

2. In the metallurgy of zinc, a condenser in which zinc fume is condensed, the resulting liquefied zinc not being retained in the condenser, an underlying container for receiving said liquefied zinc and a brick-housing provided with side-openings and horizontal flues, whereby extraneous heat may be applied simultaneously or separately either to the said condenser or the container. 95

3. In the metallurgy of zinc, a condenser in which fume is condensed but not retained, an underlying container for receiving the liquefied zinc and a brick-housing provided with horizontal and connecting vertical flues, openings in the side-walls and a sectional removable cover, whereby the rate of heat-radiation from the condenser may be controlled at all portions of its surface and sufficient heat be retained in the container to prevent the liquid metal therein from 100 105 110 solidifying.

4. In the metallurgy of zinc, a furnace for producing fume by distillation, a condenser in which fume is condensed but not retained as liquid metal, and means for so controlling the flow of fume therethrough and its rate of heat-emissivity that any desired aliquot portion of the entering fume reaches the far end of said condenser at a definite diminished temperature. 115

5. In the metallurgy of zinc, a furnace for producing fume by distillation, a condenser in which fume is condensed but not retained as liquid metal, and means for so

controlling the flow of fume therethrough and its rate of heat-emissivity that essentially all of the entering zinc-fume is condensed when the fall of temperature will 5 have reached 750° to 700° C.

6. In the metallurgy of zinc, a furnace for producing fume by distillation, a condenser in which a major portion of the fume is condensed to liquid metal and attached 10 to dust-precipitating prolong provided with winged baffle-plates, forming sub-compartments along the bottom thereof, whereby progressive concentrations of zinc-cadmium or cadmium-zinc powder are collected and 15 may be separately removed.

This specification signed and witnessed the fourteenth day of June, A. D. 1916, in the city of New York, borough of Manhattan, State of New York, by—
